UNITED STATES PATENT OFFICE.

OTTO SCHUERMANN, OF MILWAUKEE, WISCONSIN.

BILLIARD-CUE.

983,938.

Specification of Letters Patent. Patented Feb. 14, 1911.

Application filed October 22, 1910. Serial No. 588,410.

To all whom it may concern:

Be it known that I, OTTO SCHUERMANN, a citizen of the United States, residing at Milwaukee, county of Milwaukee, and State of Wisconsin, have invented new and useful Improvements in Billiard-Cues, of which the following is a specification.

My invention relates to improvements in billiard cues, and pertains more especially to the device for fastening the tip to one end of the staff.

The construction of my invention is explained by reference to the accompanying drawings, in which—

Figure 1 represents a side view of one end of the staff, part in section, provided with my improved tip also shown in section. Fig. 2 represents a section of the tip removed from the staff. Fig. 3 represents a bottom view of the tip. Fig. 4 represents a top view of the fastening device by which the tip is secured to the staff, and Fig. 5 represents a modified form of a billiard cue, part in section, as the same is constructed when the staff is provided with an end piece formed of ivory or the like, and in which the tip retaining screw is secured directly to the end of the staff.

Like parts are identified by the same reference numerals throughout the several views.

1 is a staff which is of ordinary construction.

2 is a fastening plate, which is secured to the end of the tip by a plurality of nails 3.

4 is a tip retaining screw, which is formed integrally with or rigidly secured to the plate 2 in any convenient manner, preparatory to fastening the plate 2 to the end of the cue. The plate 2 is preferably provided with a plurality of barbs 5, which are formed integrally therewith by turning up a portion of the fastening plate, as indicated in Fig. 1. 6 represents the tip, which is formed of leather or the like. It will be understood that when the tip retaining screw and plate have been thus secured to the staff by the retaining nails, the tip 6, which is preferably made of leather, is first provided with a central aperture 6', when it is turned down on the retaining screw 4. As the tip is being thus turned down, its edges are curved upwardly slightly as they

pass over the points of the barbs 5 until the central portion of the tip is brought down in close contact with the upper surface of the fastening plate 2. When this is done, the tip is forced downwardly above the barbs 5 by the tap of a hammer, or in any other equivalent manner, when the protruding ends of the bars are caused to penetrate the surface of the tip as its marginal edges are brought into contact with the end of the staff around the periphery of the fastening plate 2, whereby the tip is prevented from turning on the supporting screw and becoming loose as it might otherwise do if not retained in place by such barbs.

By the modified form shown in Fig. 5, the fastening plate 2 and nails 3 are dispensed with and the tip retaining screw 7 is made of greater length, when it is secured in place in screw-threaded bearings formed directly in the upper end 8 of the staff, the upper end 8 being formed as stated of ivory or other hard substance, which rigidly retains the screw 7 in place. When this is done, a plurality of barbs 9 are inserted in the upper end of the staff, as shown in Fig. 5, when the tip 10 is screwed down on the upper end of the retaining screw 7, as previously described, until the center of the tip is brought firmly in contact with the upper end of the staff and when this is done, the sides of the tip are forced down, as stated, by the taps of a hammer, or in any similar manner, until the upper ends of the barbs are caused to penetrate the tip, when they prevent the tip from unscrewing and becoming loose.

Having thus described my invention, what I claim as new, and desire to secure by Letters Patent, is—

1. The combination with the staff of a billiard cue, of a screw projecting from the longitudinal center of one end of said staff, a plurality of barbs projecting from the end of said staff at the sides of said screw, and an elastic tip provided with a central aperture for the reception of said screw, said barbs being adapted to penetrate the surface of said tip and prevent the same from turning on said screw and becoming loose.

2. The combination with the staff of a billiard cue, of an integrally formed screw

and screw supporting disk, means for securing said disk and screw to one end of said staff, a plurality of barbs projecting from the surface of said disk, and a leather tip 5 provided with a central aperture for the reception of said screw, said barbs being adapted to penetrate the opposing surface of said tip and prevent the same from turn-

ing on said screw, all substantially as and for the purpose specified.

In testimony whereof I affix my signature in the presence of two witnesses.

OTTO SCHUERMANN.
